UNITED STATES PATENT OFFICE.

WILLIAM GIBSON, OF PITTSBURGH, PENNSYLVANIA.

BRAKE-SHOE.

1,349,128.

Specification of Letters Patent. Patented Aug. 10, 1920.

Application filed August 16, 1919. Serial No. 317,896.

To all whom it may concern:

Be it known that I, WILLIAM GIBSON, a citizen of the United States, and a resident of Pittsburgh, in the county of Allegheny 5 and State of Pennsylvania, have invented a new and useful Improvement in Brake-Shoes; and I do hereby declare the following to be a full, clear, and exact description thereof.

10 My invention relates to brake-shoes, and has special reference to the class of brake-shoes which are provided with an inclosed metallic casing around a filling or body of frictional material for engagement with a 15 wheel in braking.

The object of my invention is to provide a cheap, simple and efficient form of a brake-shoe, wherein the ends or sides of such shoe will not cut into or wear down the 20 tread or throat of the wheel on which it is used, and one in which such ends or sides will wear down evenly and uniformly with the filling of frictional material.

A still further object of the invention is 25 to keep the metal of the casing or cap of the shoe from engaging the wheel when in use, so that when the shoe is worn down to such metal very little is left of the shoe and it then can be scrapped.

30 To these ends my invention consists, generally stated, in the novel arrangement, construction and combination of parts, as hereinafter more specifically set forth and described and particularly pointed out in the 35 claims.

To enable others skilled in the art to which my invention appertains to construct and use my improved brake-shoe, I will describe the same more fully, referring to the 40 accompanying drawings, in which:

Figure 1 is a plan or back view of a brake-shoe embodying my invention;

Fig. 2 is a side elevation, partly in section, of the same;

45 Fig. 3 is a bottom plan view of the shoe;

Fig. 4 is a cross-section of the shoe on the line 3—3, Fig. 2;

Fig. 5 is an end view of the shoe;

Fig. 6 is a sectional view showing one end 50 of the shoe; taken on the line VI—VI Fig. 1; and

Fig. 7 is a perspective view of one of the end plates.

Like symbols of reference herein indicate 55 like parts in each of the figures of the sheet of drawings.

As illustrated in the figures of the drawings, my improved brake-shoe is shown at *a* and has the usual shape or curvature, such shoe being provided with an inclosing 60 casing or cap or supporting member 1 and a frictional filling or body member 2 of frictional material inserted in said casing or cap in any suitable manner. This filling member 2 is adapted to engage with the 65 wheel and the rubbing or frictional action of the brake-shoe upon the wheel is exerted by such frictional member, which consists of any suitable material, such as cast iron or composition of matter or other material 70 secured within the casing or cap 1 to exert proper and sufficient friction upon the periphery of the wheel without the imposition of undue or excessive wear thereon and the loss of wheel metal consequent thereto, 75 and such compositions are of a character familiar to those skilled in the art.

The casing or cap 1 is formed from any suitable material, preferably from band, sheet, plate or other metal having a substantial degree of strength and durability, such as malleable, wrought or other steel or iron, and when formed from sheet or plate metal it is pressed or bent by suitable dies into a structure having an integral back wall 3, 80 side lips 4 and end lips 5, as well as being open at the front for the insertion of the filling member 2 and curved substantially in accordance with the periphery of the car wheel on which the brake-shoe is to be 85 used. The end lips 5 are cut away at their inner ends, as at 5', and this with the short side lips 4 allows for providing the deep corners 4' on the casing 1 between such lips 4 and 5 to support the filling member 2 and 90 plates 9.

The usual supporting lug 6 is connected or fixed to the back 3 of the casing or cap 1 in any suitable manner for connecting the shoe *a* to the ordinary approved brake-head 100 or hanger (not shown) and is preferably separate therefrom, as shown, by having the inner ends 7 passed through slots 8 in said back and turned against the inner face of the same to connect said lug to said casing 105 or cap. Short bearing surfaces 7 are formed adjoining the ends on the back 3 of the casing 1 which are adapted to bear against bearings on the ends of the brake-head or hanger, and such bearings are preferably 110 recessed, as at 7'. Central or intermediate bearings on the head or hanger are adapted

to abut against said back wall 3 of the casing or cap 1 and on each side of the lug 6.

In the formation of the brake-shoe *a*, after the metallic cap or casing 2 is formed, with the lug 6 connected to the back 3 in any suitable manner or as described, then the end and side pieces or plates 9 are inserted within the casing and then the material composing the filling member 2 is inserted in such casing or cap. These end and side pieces or plates 9 when so placed within the casing or cap 1 and against the filling member 2 will form the end and side walls of the finished shoe *a* and assist with such casing in holding the material comprising such member in place, and such pieces or plates are made of any convenient relatively softer material, what is commonly known as vulcanized fiber having been found satisfactory in practical use. The side pieces or plates 9 can be formed of different thicknesses, and if desired, of the same thickness as the side lips 4 on the casing or cap so that their exterior surfaces are flush with the exterior surfaces of said lips and thus strictly conform in shape and size to the Master Car Builders' standards; and in order to hold such plates against said lips and allow such flush surfaces to be obtained, the plates are provided with a turned or bent portion 10 at their inner or upper edges which forms seats 11 for the reception of the lower or outer end edges of said lips. The side pieces or plates 9 are also provided with a recessed or cut-away portion 12 at their ends, which form a shoulder 13 for the purpose hereinafter described.

The end pieces or plates 9 fit within the casing or cap 1 and against the end lips 5 and they are provided with a recessed or cut-away portion 12 in the sides of the same, which form a lug 13, so that said lug will rest against the shoulders 13 on the side plates 9, and the ends of said plates will fit within the recesses 12 in the end plates. The inner edge 9' of the end plates 9 fit within recesses 7" of bearings 7, and such plates can also be provided with the shoulder 11' on the same for fitting against the ends of the lips 5 thereby allowing the exterior surfaces of the said plates and lips to become flush with each other and thus conform to the Master Car Builders' standard.

Various other modifications and changes in the design and construction of my improved brake-shoe may be resorted to, without departing from the spirit of the invention or sacrificing any of its advantages.

In the use of the term "soft" in the above specification and in the claims it will be understood that the material used for the end and side plates or pieces of the brake-shoe will be flexible and resilient and is of such a nature as to be worn away itself by fric-

tion rather than cause the wearing away of the wheel to which the brake-shoe is applied, while such term also includes such material which will not melt from the heat of such wheel on high-speed passenger trains, and thereby form a tempered or hard material as will tend to cut into and injure such wheel. It has been found that the same raw material as the regular vulcanized fiber when properly treated and pressed or formed to shape will answer the purposes desired.

It will thus be seen that my improved brake-shoe will prevent any possibility of injury to or the uneven wearing of the wheel throat or tread and will also enable the filling, ends and sides of the shoe to wear down evenly, uniformly and together, while such form of shoe will also avoid any excessive wear on the wheel by the ends and sides of the shoe and enable a strong and durable enclosure to be formed for the filling material, while the casing or cap when so formed will eliminate waste and scrap in its manufacture. It will also be seen that in the use of my improved brake-shoe, the metal of the casing or cap will be kept from engaging with the wheel, so that the shoe can be used until it is worn down to such metal, thereby enabling only a small portion of such shoe to remain after being used to the limit, so that it can be scrapped without great loss in the material composing the shoe, while the ends and sides of the filling member will also be protected by the side and end plates and such plates will assist the cap in holding the filling member in place.

What I claim as my invention and desire to secure by Letters Patent is:

1. A brake - shoe having a supporting member and a filling member, and separate end supporting plates formed of soft material and held by the co-action of the filling member and the supporting member, with the exterior surfaces of the end plates flush with the outside surface of the supporting member.

2. A brake - shoe having a supporting member and a filling member, and separate end supporting plates formed of soft material and supported in said members, the back portion of the end plates being offset inwardly to form a seat therein for the reception of the end of the back plate.

3. A brake - shoe having a supporting member and a filling member, and separate end supporting plates formed of vulcanized fiber and supported in said members, the back portion of the end plates being offset inwardly to form a seat therein for the reception of the end of the back plate.

4. A brake-shoe having a supporting member and a filling member, and separate end supporting plates formed of a fibrous material and supported in said supporting mem-

- ber and by said filling member, the back portion of the end plates being offset inwardly to form a seat therein for the reception of the end of the back plate.
- 5 5. A brake-shoe having a supporting member and a filling member, and separate end supporting plates formed of vulcanized fiber and supported in said supporting member by the same and by said filling member,
- 10 the back portion of the end plates being offset inwardly to form a seat therein for the reception of the end of the back plate.
6. A brake-shoe having a supporting member and a filling member, said supporting member having end lips, and separate end supporting plates formed of a soft material supported between said lips and said filling member, the back portion of the end plates being offset inwardly to form a seat
- 15 therein for the reception of the end of the back plate.
7. A brake-shoe having a supporting member and a filling member, said supporting member having end lips, and separate end supporting plates formed of vulcanized fiber supported between said lips and said filling material, the back portion of the end plates being offset inwardly to form a seat therein for the reception of the back plate.
- 20 8. A brake-shoe having a supporting member and a filling member, said supporting member comprising a cap having an integral back and end lips, and separate end supporting plates formed of a soft material and supported in said end lips by the same and by said filling member, the back portion of the end plates being offset inwardly to form a seat therein for the reception of the back plate.
- 25 9. A brake-shoe having a supporting member and a filling member, said supporting member comprising a cap having an integral back and end lips, and separate end supporting plates formed of vulcanized fiber
- 30 and supported in said end lips by the same and by said filling member, the back portion of the end plates being offset inwardly to form a seat therein for the reception of the back plate.
- 35 10. A brake-shoe having a supporting member and a filling member, said supporting member comprising a cap having an integral back and end lips, and separate end supporting plates formed of a soft material supported between said members by said side plates.
- 40 11. A brake-shoe having a supporting member and a filling member, separate side plates, and separate end plates formed of a fibrous material supported between said members and by said side plates.
- 45 12. A brake-shoe having a supporting member and a filling member, separate side plates, and separate end plates formed of a soft material supported between said mem-
- bers by connections between said side and end plates.
- 50 13. A brake-shoe having a supporting member and a filling member, separate side plates, and separate end plates formed of a fibrous material supported between said members by connection between said side and end plates.
- 55 14. A brake-shoe having a supporting member and a filling member, separate side plates, and separate end plates formed of a soft material supported between said members by a lug on said end plates engaging with a shoulder on said side plates.
- 60 15. A brake-shoe having a supporting member and a filling member, separate side plates, and separate end plates formed of a fibrous material supported between said members by a lug on said end plates engaging with a shoulder on said side plates.
- 65 16. A brake-shoe having a supporting member and a filling member, said supporting member having an integral back, end and side lips, separate side plates and separate end plates formed of a soft material and supported between said filling member and said end lips by connections on said end plates and by said filling member.
- 70 17. A brake-shoe having a supporting member and a filling member, said supporting member having an integral back, end and side lips, separate side plates and separate end plates formed of a fibrous material and supported between said filling member and said end lips by connections on said side and end plates and by said filling member.
- 75 18. A brake-shoe having a supporting member and a filling member, said supporting member having an integral back and side lips, separate side plates and separate end plates formed of a soft material and supported between said filling member and said end lips by a lug on said end plates engaging with a shoulder on said side plates and by said filling material and said end lips.
- 80 19. A brake-shoe having a supporting member and a filling member, said supporting member having an integral back and side lips, separate side plates and separate end plates formed of a fibrous material and supported between said filling member and said end lips by a lug on said end plates engaging with a shoulder on said side plates and by said filling material and said end lips.
- 85 100 In testimony whereof I, the said WILLIAM GIBSON, have hereunto set my hand.
- 90 105 110 115 120

WILLIAM GIBSON.

Witness:

J. M. GEOGHEGAN.
